UNITED STATES PATENT OFFICE.

GEORGE W. DUNGAN, OF MOUNT JOY, AND CHARLES E. HOOVER, OF STRASBURG, PENNSYLVANIA.

WASHING-MACHINE.

1,047,181.

Specification of Letters Patent. Patented Dec. 17, 1912.

Application filed May 26, 1911. Serial No. 629,674.

To all whom it may concern:

Be it known that we, GEORGE W. DUNGAN and CHARLES E. HOOVER, citizens of the United States, residing at Mount Joy and 5 Strasburg, respectively, in the county of Lancaster and State of Pennsylvania, have invented certain new and useful Improvements in Washing-Machines, of which the following is a specification.

10 Our invention relates to washing machines of that type illustrated in Patent No. 823,323, dated June 12, 1906, wherein opposed scrubbing boards are provided between which the clothes are pounded and 15 scrubbed, and means for reciprocating one of said boards and also giving a rotative movement thereto.

The primary object of our invention is to 20 improve the details of construction of this type of machine so as to provide a device in which the various parts are readily detachable from each other to permit the device to be packed into small compass and so 25 economize in the shipping or the transportation of the same, and also so as to permit the device to be readily taken apart for cleaning or packing and readily applied to any tub within which the machine is 30 to be mounted.

35 A further object is to provide a washing machine in which the parts may be clamped upon any ordinary tub, the parts being adjustable so as to adapt the same machine to be used with tubs of various sizes.

40 A further object is to provide means whereby the plunger carrying one of the scrubbing boards or presser boards may be either reciprocated or rotated without removing the various parts from the tub.

45 Our invention is illustrated in the accompanying drawings wherein:

Figure 1 is a perspective view of a tub with my washing machine applied thereto. Fig. 2 is a detail fragmentary perspective view of the actuating lever, the plunger rod, 50 the clip for holding the actuating lever to the plunger rod, the link connecting the supporting bar to the extremity of the actuating lever and the clip for holding the link in place. Fig. 3 is a transverse vertical section of a tub provided with my invention, the transverse bar, the plunger actuating lever and presser being shown raised in dotted lines. Fig. 4 is a perspective detail view of the plunger yoke. Fig. 5 is a per-

spective view of one of the tub clamps. Fig. 6 is a perspective view of the lever for operating the tub clamp. Corresponding and like parts are referred to in the following description and indicated in all the views of 60 the accompanying drawings by the same reference characters.

Referring to the drawings, 2 designates a tub of any ordinary or usual character, it being one of the points of our invention 65 that it may be used on any tub and is adjustable to tubs of various sizes. The washing machine is supported upon the tub by means of a transverse bar 3. This bar has a length rather greater than the diameter 70 of any ordinary tub, and at one end is provided with an opening 4 for engagement with the pivot pin of a clamp. This clamp, illustrated in detail in Fig. 5, comprises a U-shaped clip 5 extending over the edge of 75 the tub and having downwardly extending bifurcated legs 6 on one side and a downwardly extending leg 7 on the other side, these legs or prongs embracing the tub.

The leg 7 is outwardly bent at its end 80 and provided with a headed stud 8 for engagement with a cam lever 9, illustrated in Fig. 6. This cam lever 9 is formed at one end with a rounded head 10, the inner face of this head being formed with notches 11 85 and 12, either of which may be engaged with the stud 8. It will be seen that the notches 11 and 12 are eccentric to the rounded face of the head 10 so that when the clamp is turned into a position where the handle 90 thereof is parallel to the wall of the tub, the cam shaped head will engage against the side of the tub and lock the clip 5 in tight engagement with the tub.

The clip 5 is formed with an upwardly 95 projecting lug 13, from which projects a pivot stud 14 with which the opening 4 in the bar 3 engages. Pivoted to the ear or lug 13 by means of the pivot 13^a is the guard 15 which is U-shaped in cross section. When 100 turned down in the position shown in Fig. 3, one end 15^a of this guard engages over the end of the pivot bolt 14 and holds the bar 3 in engagement with the pivot bolt or pin. When this guard is turned upward or at 105 right angles to the position shown in Fig. 5, the end 15^a will be shifted out of engagement with the end of the stud 14 which forms the pivot bolt or pin and thus permit the bar 3 to be withdrawn laterally from its 110

engagement with the pin 14. When the guard is down in the position shown in Fig. 5, it will prevent any disengagement of the bar 3 from the pivot pin 14 and yet permit 5 a pivotal movement of the bar 3. It will be noted that the guard 15 is held in the position shown in Figs. 3 and 5 by its own weight but that it may be very easily turned upward to a position to permit the removal 10 of the bar 3. In order to hold the other end of the bar 3 in engagement with the tub and yet permit it to be disengaged therefrom when needful, we provide the clip 16, illustrated in Fig. 3, which comprises a U-shaped 15 body bifurcated at its outer end and provided with the opposed lugs 17 through which passes a pin 18. A lever 19 having an eccentric head formed with a notch engages with the pin 18. When the lever is 20 turned down to the position shown in Fig. 3, this clamping lever will engage the edge of the tub and hold the clip 16 in place thereon. The clip is formed with an upwardly turned ear 20 in which is pivotally 25 mounted the angular finger 21. When this is turned up in the dotted line position shown in Fig. 3, the bar 3 may be removed from its engagement with the clip. When it is turned down, however, it extends over 30 the bar 3 and holds the bar 3 to the clip 16. We have thus provided means at both ends of the bar 3 whereby the bar may be held upon the tub. These clips 5 and 16 may be applied anywhere upon the tub and either 35 they themselves may be detached from the tub or the bar 3 may be detached from the clips whenever desired.

Shiftably mounted upon the bar 3 is a yoke comprising, as illustrated in Fig. 4, a 40 curved body portion 22, the ends of which are outwardly bent as at 23 and 24 so as to contact with the face of the bar 3. The upper and lower ends of the flange 23 are formed with lips 25 embracing the upper 45 and lower edges of the bar 3, while the flange 24 has a continuation 26 which is bent parallel to the flange 24. The flange 24 and the continuation 26 are formed with registering perforations 27 through which a detachable 50 locking pin 28 passes, this locking pin being formed with an angular handle.

The perforations 27 are so placed that when the yoke is upon the bar 3, the lower edge of the bar 3 extends across these perforations. The locking pin is not quite round but is flat on one side so that when the pin is disposed with its handle in a vertical position, the flat side 28 of the pin will slip into the perforations 27 beneath the bar 3. 55 When, however, the pin is turned to a position where its handle is not vertical, the rounded edge of the pin will jam upon the bar 3, thus holding the yoke in its adjusted position upon the bar 3. This locking pin 60 may be either permanently attached to the

clip or detachable therefrom as desired. The yoke 22 may be shifted along the bar 3 to any desired extent and this adjustability is necessary in order that the plunger may be centered relative to the tub.

Normally disposed within the curved portion 22 is a plunger 29 which is connected at its lower end to a presser board 30 formed with perforations 31 and having a plurality of transversely extending ribs 32 on its under face. The plunger board is preferably attached to a spider 33 fastened to the top of the plunger board, and this spider is formed with a socketed hub 34 within which is pinned a section 35 of the plunger rod. 70 This section is cut away as at 36 and formed with a pin receiving recess 37. The plunger rod 29 is also cut away at its lower end so as to mate with the upper end of the section 35 and is provided with a pin 38 which extends into the recess 37.

Surrounding the plunger rod is a sleeve 40 which is shiftable upon the plunger rod and is slightly conoidal in shape. When this sleeve is depressed in the position shown 90 in Fig. 3, it engages over the joint between the section 35 and the section 29 of the plunger rod and holds the sections in locked engagement with each other. By removing the sleeve, the sections may be released from 95 their locked position and the plunger rod lifted without lifting the presser board. When the machine is packed the plunger rod 29 is detached from its engagement with the presser board. The upper end of the 100 plunger rod is cut away so as to form an ear 41 having projecting from it the pin 42. The operating lever 43 is formed at its middle with a perforation to receive the pin 42. A clip 44 formed of a U-shaped member 105 adapted to embrace the lever 43 is provided, one wing of this member being formed with an arcuate slot 45 which engages with the pin 42 when the clip is in place. This clip prevents the accidental detachment of the 110 lever 43 from the plunger rod but by removing the clip, the lever may be readily detached from the plunger rod.

One end of the operating lever 43 is formed with a handle while the other end 115 is provided with a perforation 47 and with a pivoted guard 48 which may be turned down into registration with the perforation, this guard having a flange 49 which when the guard is turned down rests upon the end of the lever is shown in Fig. 3. A link 50 connects the end of the lever to the supporting bar 3. This link is pivoted to the supporting bar 3 adjacent to the perforation 4 and at its upper end is angularly 120 bent as at 51 so that it may be engaged in the perforation 47 and is held in place by the guard 48.

The scrubbing board 52 consists of a circular board approximating the size of the 130

bottom of the tub which is preferably perforated and which is provided with a series of transversely extending ribs 53 which under ordinary circumstances extend at right angles to the ribs 32. The board 52 is preferably supported in its position at the bottom of the tub by a plurality of spring arms 54 which are formed integral with feet 55 attached to the under side of the presser board 52. The upwardly extending arms 54 being resilient act to hold the presser board in position at the bottom of the tub, while permitting its ready detachment when desired. It will be seen that these spring arms 10 also act to center the scrubbing board in the tub, and that the feet formed integral with the arms raise the bottom of the scrubbing board above the bottom of the tub so that the water may freely circulate.

20 The operation of our invention will be obvious from what has gone before. After the parts have been attached to the tub, the presser board 30 is lifted out of the tub as shown in dotted lines in Fig. 3 and clothes 25 are placed in the tub. The presser board is then turned downward and the bar 3 is clamped in place upon the clips 16 by means of the pivoted finger 21. The handle 43 is then reciprocated either manually or by machinery, and the reciprocations of the presser board act to suck and force the water through the clothes, thus very rapidly and effectively cleansing the clothes. Either before or after this operation the clothes may 35 be rubbed by rotating the presser board. This is secured by detaching the link 50 from its engagement with the end of the handle 43, whereupon the handle may be used as a lever to rotate the plunger rod 29. The 40 lever 43 affords means whereby considerable power may be applied to the plunger, thus giving a thorough rubbing action to the clothes, the clothes being rubbed between the upper presser board and the lower scrubbing board 45 and the ribs 32 and 51 acting to thoroughly scrub the clothes and also squeezing them so that the water will be forced therethrough. By providing for both a reciprocating movement of the plunger and a rotary 50 movement, I secure a very thorough cleansing action. If it is desired in placing the clothes in place in the tub or removing them therefrom, the plunger, the actuating lever and the presser board 30 may be entirely 55 disconnected from the tub by simply lifting the guard 15 and the finger 21, thereby permitting the supporting bar 3 to be disengaged from the clips 5 and 16. If the device is to be applied to a tub of different 60 size, the plunger may be readily centered by sliding the yoke 22 along the bar 3 until the center of the tub is reached and then again clamping the yoke to the bar 3. It will be obvious, of course, that the link 50 65 will shift in one direction or the other so as

to permit the stud 42 on the plunger to enter the central perforation on the lever 43. It will be seen that these various clips and clamps permit the device to be very cheaply made, permit it to be readily packed in 70 small compass and permit it to be readily set up or taken down, and that by providing adjustable clips or tub clamps upon the rod 3, the supporting rod may be used for tubs of various sizes, and that by providing the yoke 22 the plunger rod may be properly centered with relation to any particular sized tub. In order to secure a greater suction when the plunger is drawn up so as to draw the water with more force 75 through the clothes, I may provide the valve plate 55 as illustrated in Figs. 1 and 3, this valve plate being circular and having approximately the size of the scrubbing board 80 30. The valve plate fits loosely over the hub 34 and is so formed as to fit over the spider 33. Normally the valve plate 55 rests upon and closes the openings 31. When the plunger is forced downward, the water rushes up through these openings 31, lifting 85 the valve plate. When, however, the plunger is raised, the weight of the water will close the valve plate and as a consequence the board 30 will exert a sucking action and draw the water very powerfully through the 90 clothes being washed.

Having thus described our invention, what we claim as new is:—

1. A washing machine attachment including a supporting bar adapted to extend 100 across a tub, and provided with adjustable means for engaging the sides of a tub, a plunger, a yoke embracing the plunger and permitting the plunger to have vertical slideable movement, said yoke being slidably 105 mounted on the supporting bar, and means for detachably engaging the yoke with the supporting bar in adjusted position.

2. A washing machine attachment including a supporting bar adapted to extend 110 across a tub, and provided with adjustable tub clamping means, a plunger, a yoke comprising a curved body portion embracing the plunger and permitting the plunger to have 115 vertical sliding movement, said body portion having end flanges, oppositely disposed ears on one end flange slidably engaging the bar, an ear formed on the other flange and bent over to embrace the supporting bar, and a cam pin extending through the last 120 mentioned ear and flange and engaging against the edge of the supporting bar.

3. A washing machine attachment including a supporting bar, tub clamps mounted on the bar, a plunger rod mounted for vertical movement on the supporting bar, an actuating lever, a link detachably connecting the actuating lever at one end to the cross bar, the plunger rod and lever being provided one with a projecting stud and the 125 130

other with a perforation in which the said stud engages, and a detachable clip embracing the end of the plunger rod and the adjacent portion of the lever and extending over said stud, whereby to prevent the disengagement between the lever and plunger rod except upon a removal of the clip, said clip having portions thereof detachably engaging the pin and acting to prevent the removal of the clip from the lever by a direct movement at right angles to the lever.

4. A washing machine attachment including a supporting bar, tub clamps on the supporting bar, a plunger rod mounted for vertical movement on the supporting bar, an actuating lever, a link pivoted at one end of the supporting bar and having an angular projection adapted to engage through a perforation in the end of the actuating lever, and a guard plate pivoted to the end of the actuating lever adjacent the said perforation and offset to engage over the link when in place to hold the link engaged with the actuating lever.

5. A washing machine attachment including a supporting bar adapted to extend across a tub, tub clamps on the bar, a yoke adjustably mounted on the bar, a plunger rod passing through the yoke, an actuating lever for the plunger rod, and a presser disk attached to the lower end of the plunger rod, the plunger rod being made in two mating sections, one of the sections being provided with a pin engaging with the perforation in the adjacent end of the other section, and a collar disposed upon the plunger rod and movable over the joint between the two sections.

6. A washing machine attachment including a supporting bar adapted to extend across a tub, a plunger rod mounted for vertical movement on the supporting bar, an actuating lever, a link detachably connecting the actuating lever to the cross bar, said ac-

tuating lever being connected to the upper end of the plunger rod, a tub clamp having a stud engaging through a perforation in one end of the cross bar and forming a pivot for the cross bar, a guard plate mounted on the clamp and movable over the stud to hold it in place, a tub clamp slidably mounted upon the bar and comprising a clip for embracing the edge of the tub, means for attaching the clip to the tub, and a pivoted finger rotatable into a position to embrace the supporting bar.

7. A washing machine attachment including a supporting bar, a plunger rod mounted upon the supporting bar for vertical movement, an actuating lever, a link connecting the actuating lever with the supporting bar, and tub clamps on the supporting bar, one of said clamps comprising a fork embracing the sides of the tub, a cam shaped lever detachably engaging the fork and movable in a position to clamp the fork against the tub, an upwardly projecting ear on the clamp, a pin on the ear engaging in a perforation in the end of the supporting bar, and a pivoted guard rotatable to a position to embrace the ear and the supporting bar, the other clamp comprising a fork engageable over the tub, a cam shaped clamping lever detachably engaged with the fork, an ear on the fork extending upward, and a pivoted finger on said ear rotatable to a position to embrace the supporting bar.

In testimony whereof, we respectively, affix our signatures in presence of two witnesses.
